UNITED STATES PATENT OFFICE.

WOOLSEY R. SEARL AND OSCAR F. CLARK, OF TIMBER LAKE, SOUTH DAKOTA.

ROTARY STEAM-ENGINE.

1,316,512.

Specification of Letters Patent. Patented Sept. 16, 1919.

Application filed March 13, 1916, Serial No. 83,990. Renewed January 27, 1919. Serial No. 273,391.

To all whom it may concern:

Be it known that we, WOOLSEY R. SEARL and OSCAR F. CLARK, citizens of the United States, residing at Timber Lake, in the 5 county of Dewey and State of South Dakota, have invented certain new and useful Improvements in Rotary Steam-Engines, of which the following is a specification.

This invention relates to steam engines 10 and more particularly to that class of engines known as rotary steam engines.

An object of our invention is to provide a rotary engine of the class described having a sliding abutment which is cam operated and 15 means being provided for automatically controlling the "cut-off" of the engine.

Another object of our invention is to provide a rotary engine having a rotary inlet controlling valve, relief ports, and an inlet 20 cut-off valve for controlling the speed of the engine.

A further object of our invention is to provide an improved arrangement of relief ports whereby upon the reversal of the direction of rotation of the engine the relief 25 ports will be automatically moved to co-operate therewith.

Other objects and advantages to be derived from the use of our improved rotary 30 engine will appear from the following detail description and the claim taken with an inspection of the accompanying drawings in which,

Figure 1 is a side elevation of the control 35 side of a rotary engine embodying the improvements of our invention,

Fig. 2 is an elevational view, one side plate and bearing member being removed, to show the interior arrangement of the engine, a 40 portion of the view being in section,

Fig. 3 is a vertical sectional view taken on the line 3—3 of Fig. 1, looking in the direction of the arrow,

Fig. 4 is a vertical sectional view taken on 45 the line 4—4 of Fig. 3, looking in the direction of the arrows,

Fig. 5 is an elevational view of the opposite side of the engine to that shown in Figs. 1 and 2, showing the gear casing removed 50 and the gears exposed,

Fig. 6 is a diametrical sectional view of the rotor taken on the line 6—6 of Fig. 2, and

Fig. 7 is an enlarged perspective view of

the inlet control valve and cut-off valve, 55 showing the same separated.

Referring more particularly to the drawings, wherein similar characters of reference designate like and corresponding parts throughout the various views, 1 designates 60 the stator or frame of our improved rotary engine, said frame having a base portion 2 formed thereon which is mounted on a floor or the like by means of bolts 3. The frame 1 is provided with an enlarged portion 4 65 formed with a power chamber 5 provided with a suitable wearing lining 6. Outlet ports 7 and 8 communicate with the chamber 5 for an obvious purpose. A rotor is mounted for operation in the power chamber 5 and is designated in its entirety by the numeral 9. The rotor 9 is formed of a cylindrical body having a plurality of recesses 10 radially arranged therein and communicating with the peripheral surface of the rotor, said 70 recesses being preferably arranged at diametrically opposite points, two being shown in the present instance. The end faces of the rotor 9 are provided with annular grooves 11, best shown in Fig. 2, said grooves 75 being located adjacent the peripheral surface of the rotor and adapted to receive segmental packing rings 12. Coil springs or the like 13 are placed between the bases of the grooves 11 and the packing segments 12 80 to maintain the latter in proximate relation to the side walls of the stator hereinafter described.

The rotor 9 is keyed as at 14 on a shaft 15 extending through the engine, said shaft being mounted in a manner hereinafter set forth. Pistons designated 16 and 17 in their entireties are mounted on the rotor 9 and are arranged in the recesses 10. The 90 pistons are practically identical in construction and therefore a description of one will suffice. Referring to the piston 16, it will be noted that this piston comprises a pair of spaced plates 18 loosely mounted in one of the recesses 10 and extending radially from 95 the rotor 9. The plates 18 have their opposing faces grooved thereon to receive keys 19, said keys engaging packing sections 20 between which is interposed a coil spring 21 for normally maintaining said packing members 100 relatively remote. The keys 19 permit of lateral sliding movement of the packing members 20, but prevent outward movement 105

of said members independently of the plates 18. Coil springs 9' serve to maintain the packing members 20 normally in snug engagement with the inner peripheral surface 5 of the power chamber.

Side plates 22 and 23 are mounted on the stator 1, said plates being of a shape substantially like that of the stator.

Bearing plates 24 and 25 provided with 10 marginal inwardly directed flanges 26 and 27 are mounted on the stator 1 and the plates 22 and 23, respectively, and are secured in position by means of bolts or the like 28. The plates 24 and 25 are provided with semi- 15 circular bearings 29 and 30, respectively, in which the shaft 15 is arranged for rotation. The upper half of the bearings are removable, semi-circular sections 31 and 32, secured by means of bolts 33 to the lower sections 20 being provided for this purpose.

We provide a sliding abutment designated 34 in its entirety, said abutment being slidably arranged in a recess 35 extending radially from the power chamber. The construction of the abutment is practically identical with the construction of the piston members 16 and 17 and therefore a detail description of the same is not thought to be necessary.

30 A rod 36 extends from the abutment 34 and is connected to mechanism hereinafter described for operating the abutment. The plate 22, of course, is necessarily slotted as at 23 to permit radial movement of the rod 35 therein.

Inlet ports are provided in our improved engine, the main inlet pipe being designated 37 and communicating with the main inlet port 38. The port 38 divides at its lower 40 end to provide a semi-circular conduit 39 terminating in inwardly directed ends 40 and 41. A cylindrical opening 42 is provided in the stator 1 and in this opening is mounted the main inlet control and reversing valve 43. The reversing valve 43 is rotatably mounted in the opening 42 and is provided with a longitudinally extending recess 44 adapted to receive the cut-off valve 45 of the engine. The valve 43 is provided with an end wall 46 over which extends a stub shaft 47 mounted in suitable bearings in the plate 22 and the plate 24, the free extremity of the shaft 47 being squared as at 48 to receive a manipulating 50 lever 49 having the usual ratchet 50 co-operating with the segmental rack 51 mounted on the bearing plate 24. The valve 43 is provided with a transversely extending recess 52, which recess upon rotation of the valve 55 alternately registers with openings 53 formed in the valve 43. The openings 53 are diametrically oppositely arranged and inlet conduits 54 and 55 communicating with the power chamber 5 on opposite sides of 60 the abutment 34 receive steam or other

power fluid through the openings 53, depending upon the position to which the valve 43 may be moved. The amount of steam supplied to the engine may be controlled by the valve 43 in an obvious manner.

70 The valve 45 is provided with a stub shaft 56, extending from one end thereof, said stub shaft having mounted thereon a gear 57, said gear being keyed to said shaft. The plate 25 with the flange 27 thereon affords a gear chamber 58 adapted to receive the gear 57, said gear 57 meshing with the idle gear 59 mounted on a stub shaft 60 carried by the plate 23, said gear 59 in turn meshing with a driving gear 61 mounted 80 upon a gear to the shaft 15. The relations of the gears are such that upon rotation of the shaft 15 the valve 45 is rotated.

In order to operate the abutment 34 we provide a cam member 62 mounted upon and 85 keyed to the shaft 15, said cam member having a peripheral surface 63 provided with outstanding lugs 64 and 65 diametrically oppositely located. The cam member 62 is provided with diametrically oppositely located extensions 66 which serve to support an annular guard member 67 provided with sinuations 68 and 69 coincident with the outstanding portions 64 and 65 referred to. An oscillating arm 70 pivoted at 71 to the 95 plate 22 is provided on one extremity with a roller 72 which is adapted to be located between the cam member 62 and the guard member 67. The opposite extremity of the arm 70 is pivotally connected by means of 100 a link 73 to a second arm 74 pivoted at 75 to the plate 22. The free end of the arm 74 is enlarged and provided with an elongated opening 76 which receives the rod 36.

We provide relief ports and controlling 105 means therefor which include preferably conduits 77 and 78 carried by the bearing member 24, said conduits communicating with the power chamber 5 on opposite sides of the abutment 34. The conduits are provided with enlargements in which slidable valve members 79 and 80 are operable, said valve members being connected by means of links 81 and 82 and levers 83 and 84 to a rocker arm 85 carried by the shaft 47. The 110 free ends of the conduits 77 and 78 communicate with an apertured enlargement 86 cast integrally with the bearing member 24, and an exhaust pipe 87 is provided.

In operation, steam is supplied to the engine by means of the pipe 37 and is admitted to the power chamber 5 against the piston 16, in the present instance, by means of the valve 45. By shifting the lever 49 from one side to the other the amount of steam supplied to the engine may be controlled and the steam may be cut off entirely by placing the lever in neutral position. When the rotor is operating the roller 72 moves between the cam 62 and the member 67, said roller 120

125 65 the abutment 34 receive steam or other 130

following the offset portions of said cam. This causes the arms 70 and 74 to be oscillated which in turn reciprocate the abutment 58. This serves to move the abutment out 5 of the path of the pistons, it being clear that the offset portions of the cam are located in alinement with the pistons, and operate slightly in advance thereof.

From the use of this engine it will be 10 seen that we are enabled to control the amount of steam supplied to the engine and the same may be easily reversed without the provision of complicated and inefficient mechanism. The periphery of the rotor is 15 preferably of greater weight than the central portion thereof, in order to impart to the same a fly-wheel action. It will also be apparent that we have provided in a rotary engine relief ports for coöperation with the 20 main control valve whereby when starting the engine no undue strain is liable to occur on the stator or on the rotor.

From the above description taken in connection with the accompanying drawings, 25 it is thought that a clear and comprehensive understanding of the construction, operation and advantages of our invention may be had,

and while we have shown and described our invention as embodying a specific structure, we desire that it be understood that we may 30 make such changes on said structure as do not depart from the spirit and scope of the invention as claimed.

What we claim as new and desire to secure by Letters-Patent is:—

In combination with a rotary engine having a valve chamber formed in the stator thereof, inlet and outlet ports communicating with said chamber, a reversing valve rotatably mounted in the valve chamber, a cut-off valve rotatable in said reversing valve, means for adjusting the reversing valve with relation to the intake and outlet ports, a power chamber, outlet conduits communicating therewith; reciprocating valves interposed in the outlet conduits, an arm secured to the reversing valve, and means for connecting said reciprocating valves with the arm.

In testimony whereof we affix our signatures.

WOOLSEY R. SEARL.
OSCAR F. CLARK.
